UNITED STATES PATENT OFFICE

2,489,290

DIRECTION FINDER

Louis John Heaton-Armstrong, London, England,
assignor, by mesne assignments, to International Standard Electric Corporation, New York, N. Y., a corporation of Delaware

Application November 15, 1945, Serial No. 628,925
In Great Britain November 28, 1944

2 Claims. (Cl. 343—121)

1

The present invention relates to radio direction finders and more particularly to antenna systems therefor comprising one or more pairs of spaced antennae, the antennae of a pair being connected by transmission lines of equal lengths and like characteristics to a radio receiver or other device for obtaining the desired indication and a non-directional antenna also coupled to said radio receiver or other device by a transmission line.

It is essential, in such systems that the signal waves at the outputs of the transmission lines at the receiver should always bear a constant phase relationship. When however, the operating frequency is changed, the phase relationship of the signal waves at the outputs of the transmission lines is changed on account of the variation with frequency of the difference in electrical lengths of the transmission lines coupled respectively to the antennae of the pairs and to the non-directional or sense antenna.

An object of this invention is to provide a direction finder antenna system of the type specified for operation over a wide band of frequencies and this object is attained in accordance with the present invention by inserting in at least the transmission lines conveying the signal waves from the pairs to the receiver or other device or in the transmission line conveying the signal from the non-directional antenna to the receiver or other device, means which automatically compensate for the divergence from a desired constant phase relationship between the signal waves at the outputs of the transmission lines at the receiver or other device.

In one embodiment of the invention to be described in detail hereinafter a phase advance network which advances the phase of the signal passed therethrough inversely as the frequency is connected in series in the transmission line from the non-directional antenna. Usually the transmission lines used for coupling the antennae to the receiver are the same except in physical length.

The said network then comprises the inversion of an artificial line or π -network which has substantially the same characteristic, namely frequency versus phase-change, as a transmission line whose length is the difference in lengths between the respective lines connecting the pairs and the non-directional antenna to the receiver or other device and maintains the phases of the outputs from the transmission lines of the pairs and non-directional antenna substantially in phase.

The invention will be better understood from

the following description taken in conjunction with the accompanying drawings, in which:

Fig. 1 shows diagrammatically a direction finder antenna system of the type specified and a receiver to which the signal waves from the antenna systems are applied;

Fig. 2 is a plan view of the system shown in Fig. 1;

Fig. 3 is a vector diagram used in the description;

Figs. 4 and 5 show suitable forms of phase retard or advance networks respectively;

Fig. 6 shows various graphical curves used in the description.

Fig. 1 shows the known antenna arrangement for a direction finder. It comprises two dipole pairs 1, 2 and 3, 4 arranged on the corners of a square of diagonal, for example not exceeding .28 the operating wave length and a non-directional antenna 5 located at the centre of the system. The pairs are connected by half-wavelength transmission lines 6 and 7 which are each crossed over at one end. The fifth antenna 5 is, as is well known, used for sense determination and provides a source of signal whose amplitude and phase are independent of the direction of arrival of the signal provided the latter lies in the horizontal plane. The dipole pairs give an output which is dependent on the direction of arrival of the signal. The phase relationships of the signal outputs from the antennae will be clear from Fig. 3. In this figure vector E_5 is the E. M. F. induced in the aerial 5 and produces a voltage V_5 at its base. Vector E_1 is the E. M. F. in antenna 1 which is in advance of E_5 for the direction of signal shown by arrow 8, Fig. 2. E_2 , the E. M. F. in antenna 2 lags on E_5 . The difference vector between E_1 and E_2 , i. e. between E_1 and E_2 reversed, i. e. E_2 is always at right angles to E_5 and is brought into phase at the receiver by the quarter wavelength lines 6. V_1 is the voltage on the line 6 at mid-point 9, it lags behind E_1 by 90° due to the quarter wavelength of line 6. E_2 is the vector of E. M. F. in antenna 2, it is reversed at 45 E_2 due to the cross over of the line 6 and, after 90° retardation in the line 6, it appears at point 9 as V_2 . The resultant of V_1 and V_2 is V_R which is in phase with V_5 . It will be noted that the resultant V_R varies in magnitude and sense with the direction of arrival of the signal.

In one direction finder as described fully in British patent specification No. 490,940 and shown schematically in Fig. 1, the outputs at 9 and 10 are fed into balanced modulators 11 and 12, which have different modulating frequen-

cies e. g. 5 kc. and 6 kc. applied from 18 and 19 respectively so that sidebands $f_0 \pm 5$ kc. and $f_0 \pm 6$ kc. are produced at the outputs of the modulators. The signal from the central aerial of frequency f_0 is fed to an amplifier 13. The three outputs are then combined at 14 and fed to further apparatus and eventually to an indicator such as a cathode ray oscilloscope to obtain a direct reading of the bearing. It is essential to have the inputs to the modulators 11, 12 in phase or anti-phase with that to the amplifier 13 from the central antenna.

When a wide band of frequencies is used it is no longer possible to keep the lines 6 and 7 between the antennae and their mid-points one quarter wavelength long at all frequencies and the resultant voltages from the pairs and the voltage from the centre antenna will no longer be inphase.

It is well known that a transmission line section may be represented by the π -network 15 shown in Figure 4, where β is the electrical length of the line in degrees, 360° being one wavelength λ . This network or artificial line is designed to produce a phase lag of θ° between the output and input voltages, and this phase lag will be very nearly proportional to the frequency applied provided that θ is less than about 120° for any of the frequencies considered. This is shown in Figure 6, curve a. The series inductance is $jZ_0 \sin \theta$ and the shunt capacities are each $-jZ_0 / \tan \theta/2$, where Z_0 is the characteristic impedance of the line. The phase lag occurring in a natural transmission line is shown in curve b. With a similar π -network in which the inductance is replaced by capacity of the same value and the capacities by inductances of the same value as shown at 16 in Fig. 5, which is the inversion of the network 15, the output voltage has a phase advance on the input voltage phase, and furthermore the angle θ of the advance varies inversely as the applied frequency as shown in Fig. 6, curve c. In accordance with this invention a network such as 16, Fig. 5, is connected in series with the central antenna, as shown for example in the input of amplifier 17 (Fig. 1) which is usually present at the central antenna. Then the quadrature phase shift between the voltages at the antennae 1, 2, 3 and 4 and the voltage at the central antenna 5, and usually produced by the quarter wave lengths of lines 6, 7 is now produced by the lines 6 or 7 and the network 16 and the signal from the central antenna is maintained in a substantially constant in-phase relationship to the combined signals from the respective pairs of antennae over a band of frequencies. An example will make this clear.

Suppose it is required to utilise a frequency band from 30-100 mc./s. (megacycles per second).

The transmission lines 6 and 7, measured between the antennae and mid-points 9, 10, are made of length equal to 67 electrical degrees at 100 mc./s. Then from Fig. 6 at 30 mc./s. the length will be twenty degrees. The inverted network 16, Fig. 5, to be put in series with the central antenna will be made 19 electrical degrees at 100 mc./s. and will be 72 degrees at 30 mc./s., see Fig. 6, curve c. The total phase shift due to the

line and the circuit in the central antenna will then be approximately 90° over the whole frequency band as shown in Fig. 6, curve d.

While the simplest and most practical embodiment of the invention has been described other more complicated embodiments will occur to those skilled in the art, for example, a phase compensation could be obtained equally well by utilising a phase retard network in the line from the non-directional antenna and phase advance networks in lines from the dipole pairs.

What is claimed is:

1. A radio direction finder antenna system for use over a broad band of operational frequencies comprising two pairs of spaced antennae, the antennae of the pairs being located at the opposite ends of the respective diagonals of a square and coupled to each other by auxiliary transmission lines of equal lengths and characteristics, and having a cross over in one half, a non-directional antenna located at the centre of said square and like means for coupling the mid-points of said auxiliary transmission lines to a radio receiver for obtaining the desired indication, and in series with the said non-directional antenna a phase advance network consisting of an inverted equivalent artificial line π -network of one half of one of said auxiliary transmission lines.

2. A radio direction finder antenna system for use over a broad band of operational frequencies comprising two pairs of spaced antennae, the antennae of the pairs being located at the opposite ends of respective diagonals and being coupled to a radio receiver for obtaining the desired indication by transmission lines of equal lengths and characteristics, a non-directional antenna coupled to said radio receiver by a transmission line, and in the line from said non-directional antenna, a phase-advance network which advances the phase of a signal wave passed therethrough by amounts substantially inversely as the frequency of said signal wave and which together with the differences in phase delays produced in the first mentioned transmission lines and the transmission line from the non-directional antenna with increase in operational frequencies, maintains the output signal waves from said first mentioned transmission lines and said line from said non-directional antenna, substantially in constant phase relationship, said transmission lines all having the same electrical characteristics and said phase advance network comprising the inverted equivalent artificial line π -network of the difference in lengths of said transmission lines.
